Obeniger Board, New Sharon Maine.

Lettered Patents.

The schedule referred to in these Lettered Patents, and making part of the same, containing a description in the words of the said Obeniger Board, himself of his improvement in Bee Hives and Honey.

Be it known that I, Obeniger Board, of New Sharon in the County of Kennebunk, and State of Maine, have invented and constructed and am applying to use a new and useful improvement in Bee Hives and Bee Houses called "Board Improved Bee House" and that the following is a true and exact description and specification thereof to wit: The houses may be made of various sizes, according to the number of bees that inhabit them. A Bee House of some dimensions of common size should be thirty nine and a half inches in length, the width on the bottom thirty three inches and from the bottom upwards fifteen inches, it is widest to twenty nine inches, from the fifteen inches to the top is forty two inches, making the whole twenty nine inches. Above the top is eleven inches, and from the top downwards called eaves, it is sloping so as to shed off the water. This sloping part or roof is hung on hinges at the top, so as to put four small hives with bees in them, into the large house, and also small boxes for the bees to make honey in, on the top of the house a cap is put to shed off the water from the joints that are made by the covers or lids. The Bee House stands on four legs made fast to it by nailing at each end. The bottom has one board ten inches wide, which runs from end to end, and to this bottom board there are on each side two small bottom boards strong by hinges, that should be let down in

in hot weather to give the bees more room to visit the hives, in the time of making honey and also to give them a fresh circulation of air and thereby facilitate their instinct labor. These bottom boards are to be put up in the fall as soon as the flowers disappear, to protect them from being robbed by their neighbors and kept so until flowers appear again. The above is a description of a beehouse for four swarms, but they may be made to suit three or two swarms in proportion to the bees that inhabit them. There are put into the earth on the middle bottom board, four hives with bees in them. These hives are made as follows. One of them sideboards are whole, the other three are made with openings, and the top is made with openings, either of long cracks running across the hive, and up and down or with round or square holes in the hives and boxes. These openings or holes are to admit the bees into the boxes and from one hive to the other; glass globes or tumblers may be put in, instead of boxes. The above described four hives are of equal sizes. They are fifteen inches across the top by nine and three quarters inches. In height seventeen and three eights inches. The dimensions of the bottom are nine and three quarters inches by eight and one half inches. On the sides of these hives are placed small boxes thirteen deep, but in some houses they are made only one or two deep. The above have three tiers on each side of the four hives. There are twenty four boxes on the top, in them whole hives are usually live bees, but they are sometimes made with top. This is one way of bees putting instead of the above described hives during the time of swarming, and the hives are put into the large house. The openings on the sides of the hives are opened and the bees permitted to amalgamate together, and thereby make but two families in the large house, by admitting two streams

swarms together they make more honey and winter better. By having two families made off from swarms, in the same small house, their winter heat causes a more circulation separated there being only a half-inch partition between them. The frost affecting each and first causes the bees to draw towards the warmer part of the hive, which brings into the centre of the house on each side of the partition, and thereby they do not suffer by the frost in the winter. The following is a description of the boxes in the beehouse, first, a Forty-eight section and seven eighty inches by six and a half and five inches deep. Twenty-four are made six and a half by three and a quarter, and five deep. The comb of the hives (in which the bees are put into the house) will become old and unhealthy in seven or eight years and by having two hives in one family one can be taken out and one empty one put in room of the full one. if the bees should fill the empty one the first season, the next season the other can be removed. The other end of the house can be managed in the same way. That the bee house is a good as when the bees were first put into it. This house is calculated to receive the bees for a long time it being so constructed that the whole of the comb in the house can be changed, and the bees make new in room of the old. The hives should be changed the first of July. What I claim as original and of my own invention is the manner of constituting and arranging the hives and boxes within the house, and the manner in which the bees communicate therewith.
